[57] CLAIM

The ornamental design for a flower pot support, as shown and described.

DESCRIPTION

FIG. 1 is a perspective view of a flower pot support showing my new design;

FIG. 2 is a front elevational view thereof;

FIG. 3 is a right side elevational view, the opposite side being a mirror image;

FIG. 4 is a rear elevational view thereof;

FIG. 5 is a top plan view thereof, the bottom plan being a mirror image; and

FIG. 6 is a perspective view of a second embodiment, the only difference being a decrease in height.
